MOUNTING FOR SWITCHES AND THE LIKE

Harold Catron, deceased, late of Logansport, Ind.,
by Walter Newman, administrator, and Frank
A. Dotterer, Logansport, Ind., assignors to
R-B-M Manufacturing Company, Logansport,
Ind., a corporation of Indiana

Application November 9, 1939, Serial No. 303,606

8 Claims. (Cl. 248—27)

The present invention relates generally to mounting means and is more particularly concerned with means for mounting electrical units, such as light and dimmer switches and starting solenoids for automobiles.

The object and general nature of this invention is the provision of mounting means for switches and the like in which the attachment of the part to be mounted can be done readily and quickly, yet the attachment is firm and secure and not likely to loosen or rattle at any time.

More specifically it is a feature of this invention to provide attaching means for switches and the like which is in the nature of a bayonet-type connection, with biased means yieldably holding the parts in position, yet permitting either connection or disconnection to be effected quickly and simply with practically one motion.

These and other objects and advantages of the present invention will be apparent to those skilled in the art after a consideration of the following detailed description of the preferred construction, taken in conjunction with the accompanying drawings.

In the drawings:

Figure 1 is a plan view of a dimmer switch and mounting embodying the present invention;

Figure 2 is an enlarged fragmentary view, taken generally along the line 2—2 of Figure 1;

Figure 3 is a view similar to Figure 1 showing parts of the switch mechanism;

Figure 4 is a fragmentary section showing the manner of securing the plunger tube and mounting bracket to the switch case;

Figure 5 is an enlarged section taken along the line 5—5 of Figure 1;

Figures 6 and 7 are perspective views, respectively, of the mounting bracket and holding spring;

Figure 8 is an enlarged fragmentary perspective view showing the action of the mounting bracket and holding spring in fastening a switch or other unit to the panel receiving it;

Figures 9 and 10 are plan and sectional views of a modified form of switch unit and mounting therefor, arranged particularly for instrument panel mounting;

Figure 11 shows the mounting cup secured to the instrument panel to receive the unit shown in Figures 9 and 10;

Figure 12 is a fragmentary view taken generally along the line 12—12 of Figure 10, certain parts being omitted for purposes of clarity; and

Figures 13 and 14 show the application of the

present invention to a starting solenoid mounting.

Referring now more particularly to Figures 1 to 8, which show a dimmer switch constructed and mounted according to the principles of the present invention, the reference numeral 1 indicates a plate or panel which may be disposed adjacent the clutch pedal so as to be conveniently accessible to the foot of the operator, and the reference numeral 2 indicates the dimmer switch 10 in its entirety. Foot dimmer switches are provided on automobiles and similar vehicles to provide for changing the light beam or beams of the headlights and, in general, consist of a unit having a movable part adapted to be depressed 15 to change a switch contact member from one position to another and depressed a second time to change the contact member back to the first position, and so on.

The switch unit 2 comprises a switch casing 3 enclosing suitable switch mechanism 4, which will be described below, and a bracket or supporting plate 5 secured to and forming a part of the switch case 3, for supporting the same. A tube 7 is also secured to the bracket 5 and encloses 20 an operating part in the form of a plunger 8 having a head 9 which is telescopically associated with the outer end of the tube 7. The plunger or rod 8 is riveted at its outer end to the head 9 and, at its inner end, extends through an opening 11 formed in the switch casing bracket 5. The switch casing 3 is completed by an insulating block or plate 14 which carries three contacts 15, 16, and 17, with which terminals 18, 19, and 20 are associated, respectively. The side 25 walls of the switch casing 3 are indicated at 21 and are provided with ears 22 (Figures 1 and 3) which are bent over the insulating block 14 to hold the latter in position.

The contacts 15, 16, and 17 are in the form of rivets, the rounded heads 15a, 16a, and 17a of which are engaged by a movable switch contact member 23, the latter consisting of an insulating plate 24 and a metallic connecting member 25. The insulating plate 24 is provided with two openings 28 and 29, the latter receiving a pin 30 which is riveted to the bottom of the switch case 3. A plate 32 is shiftably mounted for movement along the bottom of the switch case 3 and has an end 33 turned upwardly and slotted, as at 34, and interengaged in a groove 35 formed at the inner end of the plunger rod 8. The slot 34 extends along the switch, and the pin 30 extends upwardly through the slot, as best shown in Figure 5. An extruded part 36

on the bracket 5 serves to hold the end 33 in the slot 34, as best shown in Figure 5.

A contact shifting member 31 is disposed above the shiftable plate 32 and is formed with a transverse slot 38 which receives the pin 30, as best shown in Figure 5. The plate 31 is provided with an upwardly extending arm 39 which enters the opening 28 of the movable contact member 23, and the plate 31 is also provided with laterally spaced lugs 41 and 42 and rear shouldered sections 44 and 45. The movable plate 32 is provided with a pair of laterally spaced projections 46 and 47 and a forward pair of laterally spaced projections 48 and 49. A spring 51 is disposed about the pin 30 and bears at its lower end against the transversely shiftable plate 31 to hold the same down against the plate 32, and at its upper end the spring 51 bears against the shiftable contact member 23 to hold the same upwardly in engagement with the contact 15 and one or the other of the contacts 16 or 17.

With the parts arranged as shown in Figures 3 and 5, when the plunger 8 is depressed and then released, the plate 32 is moved inwardly, which first moves the projections 48 and 49 away from the lugs 41 and 42, and then the projection 46 engages the shoulder 44 and swings the plate 31 in a counterclockwise direction (Figure 3), which shifts the contact member 23 from the position connecting the contacts 15 and 17 over into a position connecting the contacts 15 and 16. The return of the plunger 8 under the influence of the spring 10 then brings the two projections 48 and 49 back into engagement with the plate 31, but on the other side of the lugs 41 and 42, which holds the plate 31 in its dotted line position (Figure 3), and thus maintains the contact member 23 in a position connecting the contacts 15 and 16 until the plunger 8 is again depressed, whereupon the plate 31 will be shifted back into its full line position (Figure 3) which swings the contact member 23 back into a position connecting the contacts 15 and 17.

The mounting bracket 5 which forms a part of the switch case 3 is of particular construction and comprises a plate having the form best shown in Figure 6. The bracket is provided with four generally rectangular openings 56 through which project tongues 57 (Figure 4) formed on the inner end of the tube 7, the tongues 57 being bent over to secure the tube 7 to the bracket 5. The bracket 5 also is provided with an extruded portion 58 (Figure 5) to which ears 59 formed on the switch case 3 are riveted, whereby the switch case is securely fixed to the bracket 5.

A pair of offset lugs 60 are formed on the bracket or plate 5 in generally diametrically opposed relation, the end portions of the lugs 60 being disposed in a plane spaced from the general plane of the bracket plate 5, as best shown in Figures 5 and 6. Generally axially directed connecting sections 61 join the lugs 60 to the plate 5, as best shown in Figure 5. One edge, as at 63, of each lug is bent outwardly to form a cam to facilitate mounting the switch in position on the panel or supporting plate 1, as will be pointed out below.

A spring 65 of generally cruciform configuration, as best shown in Figure 7, is provided with two pairs, 66, 67 and 68, 69, of arms, and a central apertured section 71 which includes four recesses 72. As best shown in Figure 5, the spring 65 is secured to the bracket 5 between the tube 7 and the central portion of the bracket plate 5,

the tongues 57 of the tube 7 passing through the notches 72, whereby the spring 65 is firmly and permanently clamped to the bracket 5. The spring member 65 is so formed that the arms 66, 67 and 68, 69 curve or angle outwardly, and the pair of arms 68, 69 are bent outwardly at the ends, as at 73, to form sections which terminate short of the sides of the arms, thereby forming cams at the corners, as indicated at 74, so as to provide cam sections to facilitate the release of the switch, as will be described below. The arms 68, 69 have their edges opposite the cam sections 74 formed as stops 76.

The panel or supporting member 1 is provided with a central opening 78 with two diagonally opposed notches 79 extending outwardly from the central opening 78, as best shown in Figure 2. The opening 78 is large enough to receive the plunger tube 7 and the cap 9, and when the switch unit is to be mounted in place on the panel or supporting member 1 the tube 7 is inserted through the opening 78 from the left side (Figure 1) of the panel 1. The switch, with its bracket 5, is brought into position so that the lugs 60 will pass through the notches 79, which brings the arms 66, 67 and 68, 69 of the spring member 65 up against one side of the panel 1 while the lugs are disposed at the other side. Then the entire switch unit is pressed against the panel 1 and rotated in a counterclockwise direction as viewed in Figure 2, which causes the cam edges 63 of the arms 60 to ride up over the edges 79a of the opening 78, the rotation of the switch being continued until the parts occupy the positions indicated in Figures 2 and 8, with the lugs 60 bearing against one side of the panel 1 and held firmly thereagainst by the curved arms of the spring member 65. By the time the lugs 60 reach the position shown in Figures 2 and 8, the spring arms 68 and 69 snap into the notches 79, whereupon the abutment edges 76 of the spring arms 68 and 69 serve to limit the rotation of the switch in this direction. The arms 68 and 69 are, however, slightly wider than the notches 79, as best shown in Figure 2, so that the cam portions 74 of the switch arms 68 and 69 lie in engagement with the edges of the notches 79 opposite the edges 79a. The spring arms 68, 69 therefore yieldingly hold the switch unit in place with the bracket 5 interlocked with the panel 1, and with the lugs 60 lying on one side of the panel and the biasing spring 65 and the major portion of the bracket on the other side (Figure 5). The other pair of arms 66, 67 of the spring 65 bear continually against the side of the panel, maintaining the lugs 60 in firm engagement with the panel 1, so that the switch unit cannot become loose and rattle, but is maintained tight at all times. When the operator steps on the plunger head 9 to actuate the dimmer switch, the lugs 60 bearing against one side of the panel 1 take the reaction of the operating force.

Since the cam edges 74 of the spring arms 68, 69 lie against the associated edges of the notches 79, it is a simple matter to detach the switch unit by rotating the same in a clockwise direction, as viewed in Figure 2, which forcibly cams the spring arms 68 and 69 out of the notches 79 and permits the switch to be turned an amount sufficient to bring the lugs 60 in line with the notches 79, whereupon the switch may be withdrawn from the panel 1.

The form of support or mounting described above is satisfactory for switches and the like which are mounted, for example, on the floor

board of an automobile, or any other location where the presence of the lugs 60 and the notches 79 at the front side of the supporting panel member is not objectionable. However, an arrangement of this kind would not be desirable for mounting a switch or other part on an instrument panel of an automobile, or any other part normally within view or decorative in nature, unless, of course, some means were provided for masking the attaching lugs and associated parts, which are more utilitarian than decorative.

Referring now to Figures 9 to 12, inclusive, the reference numeral 90 indicates a switch of the push-and-pull type, and a mounting therefor adapted to support the switch 90 on the instrument panel, with the operating member of the switch extending through an opening in the panel but without otherwise disturbing the smooth appearance of the forward side of the instrument panel. The latter is indicated by the reference numeral 91 and, according to the present invention, is provided with a cup 92 spot-welded or otherwise secured to the back side of the panel 91. The cup 92 is flanged, as at 93, this being the portion to which the spot-welding is applied, and the body portion of the cup 92 is provided with a central opening 95 and a pair of notches 96 extending from the opening in about the same formation as the opening 78 and notches 79 shown in Figure 2. The panel 91 has an opening 97 in axial alignment with the opening 95.

As best shown in Figure 10, the switch unit 90 includes a switch case 98 carrying an insulating block 99 to which terminals 101, 102, 103, and 104 are fixed, as by contact rivets, the heads of which are disposed on the inside of the insulating block 99. A movable contact member 107 is disposed for movement within the switch case 98 and comprises a plate 108 carrying a roller 109 and a pin 110, and formed at its forward end with a slotted lug 111 in which the inner end of an operating rod 112 is received. The rod is grooved, as indicated at 113, and interlocks with a slot 114 in the plate 108. A spring 116 is disposed about the pin 110 and bears downwardly at its lower end against the plate 108 and upwardly at its upper end against a movable contact block 117 which carries a metallic contact plate 118 which, in one position of the switch, connects the terminals 102 and 103 to the terminal 101 and, in the other position, connects the terminals 103 and 104 to the terminal 101. The bottom of the switch case 98 is provided with depressions 119 receiving the roller 109 to afford a sensible indication of the position of the switch. When the roller 109 is disposed in the innermost depression, the switch is in its open position.

The switch operating member or rod 112 extends outwardly through the forward end of the switch case and is slidably supported in a tubular rivet 121 which clamps an attaching bracket 122 to the forward end of the switch case. The clamping bracket 122 is, like the bracket 5 shown in Figure 6, provided with a pair of diametrically opposed offset attaching lugs 123, the ends of which are disposed in a plane parallel to but spaced from the general plane of the bracket itself. The head of tubular rivet 121 also secures a spring member 126 firmly and permanently to the bracket 122, the spring member 126 being in the general form of the spring 65 shown in Figure 5, having two pairs of diametrically opposed arms 128, 129 and 130, 131. The lugs 123 are each provided with a cam section 123a, and the spring arms 130, 131 are each provided with in-

clined cam and abutment portions 133 and 134 similar, respectively, to the cam and abutment sections 63 and 74 shown in Figure 7. An ornamental button 135 is adapted to be threaded onto or otherwise secured to the outer end of the switch operating member 112, after the switch is mounted in place. An extruded portion (not shown) on the bracket 122 enters an opening in the forward wall of the switch case so as to hold the bracket in its proper angular position.

The switch unit 90 is mounted in place in much the same way as the switch unit shown in Figures 1 to 8. The push button 135 is removed from the operating plunger 112 and then the latter is inserted through the opening 97 in the panel 91, the switch casing being turned so that the lugs 123 enter the notches 96 formed in the cup 92. The spring arms bear against the edge of the cup and when the switch is turned in the cup the cam edges 123a of the lugs 123 ride up over the edges of the notches 96, stressing the spring arms 128, 129 and 130, 131, the switch case being rotated until the spring arms 130, 131 snap into the notches 96, which holds the switch in place with the lugs 123 locked to the cup 92 in about the same manner that the lugs 60 are locked to the panel 1 in the form of the invention shown in Figures 1 to 6. The ends of the arms 130 and 131 are wider than the notches 96, so that while one edge 134 of each arm serves as an abutment engaging one edge of the associated notch 96, thereby limiting the rotation of the switch in one direction, the opposite or cam edge 133 of each arm bears against the opposite edge of the notch so that, while holding the switch in position, it permits the latter to be turned in the opposite direction to detach the same from the panel 91 when desired. After the switch has been attached in the manner just described, the push button 135 is threaded onto the operating rod 112, thereby completing the installation.

In the form of the invention shown in Figures 1 to 8, the cam sections 74 on the spring arms 68 and 69 were merely inclined portions, as best shown in Figure 7, but in the form of the invention shown in Figures 9 to 12, the cam portions 133 are formed as best shown in Figure 12, with a curved or angled part 133a and a flat displaced portion 133b, the latter lying against one side of the notched cup while the remainder of the spring arm is disposed within the associated notch, thereby holding the switch against inadvertent or accidental return movement to released position.

The present invention is not necessarily limited for use in switches in which an operating part or other member extends through the opening in the panel in which the switch unit is detachably mounted. Referring now to Figures 13 and 14, the reference numeral 140 indicates a solenoid assembly of an automobile starting system and which includes a casing 141 closed by a cap 142 and enclosing a solenoid, one end of which is grounded to the casing 141 and the other end of which is adapted to be connected to a source of energy through a terminal 143. The solenoid in the assembly shown is adapted, when energized, to connect two terminals 144 and 145, from one of which a cable extends to the body and from the other of which a cable extends to the starting motor.

The solenoid assembly also includes a mounting plate 147 which is riveted, as at 148, to one end of the casing 141. The outer end of the

mounting plate 147 is bent downwardly, as indicated at 149, and is formed with a pair of offset lugs 151 and 152 provided with cam edges 153 and 154, being of the same general configuration of the bracket shown in Figure 6. The lugs 151 and 152 are offset from the general plane of the mounting plate section 149. A coupling spring 156 of substantially the same general form shown in Figures 7 and 12 is riveted, staked, or otherwise secured to the mounting plate bracket 149, preferably at four places, as indicated at 157. The spring 156 is provided with two pairs of arms 158, 159 and 160, 161, the latter having stop edges 163 and inclined cam sections 164.

The solenoid assembly 140 is adapted for mounting in the same manner as the units shown in Figures 1 to 12 and described above. The solenoid assembly may be mounted in a plate or panel 165 of substantially the same form as the panels 1 and 91 shown in Figures 1 and 9, having a central opening 166 and two diametrically opposed notches 167 and 168. The notches are so disposed that when the lugs 151 and 152 are inserted therein and the assembly then turned, the lugs interlock back of the panel 165, and in the locked position of the solenoid assembly the spring arms 160 and 161 snap into the notches 167 and 168 for yieldingly holding the solenoid assembly in position. The cam edges 164 are disposed against the associated edges of the notches so that the solenoid assembly may conveniently be removed merely by rotating the same back to a position in which the lugs can be removed through the notches 167 and 168. It is not necessary, of course, to provide the central opening 166, since all that would be required would be the notches 167 and 168 with suitable openings or extensions to accommodate the movement of the lugs 151 and 152 into their locked position.

From the above description of the preferred means in which the principles of the present invention have been embodied, it will be noted that I have provided a mounting means for attaching an electrical or other unit in place merely by inserting suitable attaching lugs through associated openings in a supporting member and then rotating the unit into a locked position, at which time suitable spring means snap into the lug receiving recesses to prevent inadvertent or accidental backward movement of the unit to its released position while other spring arms bear continuously against the supporting member to hold the parts interlocked together. The spring arms that snap into the openings are arranged with cam edges to facilitate removal of the unit, but the provision of such cam sections does not affect their efficacy in normally holding the unit in locked or attached position. Further, the locking spring arms, particularly together with the associated pair of spring arms which normally engage the inner side of the panel at all times, provides an arrangement in which the unit cannot become loose and rattle, yet the same can be attached and detached readily, and when attached the part is automatically locked against accidental displacement.

The mounting means of the present invention is particularly adapted for the attachment of switches and similar electrical units to thin metal panels, such as are usually found in the instrument boards and other parts of automobile bodies, and the present invention is also particularly adapted for electrical units in which operating parts are required to extend through the

panel or supporting means on which the unit itself is mounted although the present invention is not to be limited to mounting units of this latter character.

From the above, therefore, it will be apparent that the present invention is not necessarily limited to the particular details shown and described above, but that, in fact, widely different means may be employed in the practice of the broader aspects of our invention.

What we claim, therefore, and desire to secure by Letters Patent is:

1. The combination of a first member having a pair of lugs, a second member having opening means to receive said lugs and to accommodate rotative movement of said first member to carry said lugs into locking engagement with the second member, and a pronged spring carried by said first member and rotatable therewith, said spring having one part bearing against said second member for maintaining said lugs tightly in engagement with said second member and another part positioned to engage in portions of said opening means when said first part has been turned into locking position.

2. In combination, a supporting plate having lug receiving openings, a bracket having a body portion in one plane and two lugs having oppositely angled ends disposed in a parallel plane spaced to receive said plate therebetween, and a spring carried by said bracket and provided with two arms, one bearing against said plate at the bracket side thereof and the other positioned to snap into one of said openings after the lugs have been inserted into the openings and the bracket moved to interlock said lugs with the plate.

3. The combination with a supporting member having a slot, of a bracket, a pair of lugs on said bracket adapted to be inserted through said slot from one side of the supporting member and to engage the opposite side thereof when the bracket is turned, and spring means carried by said bracket and rotatable therewith into a position to engage in said slots when said bracket is turned to carry said lugs into a position engaging said opposite side of the supporting member, said spring means having cam portions engageable with the sides of the slots to facilitate turning said bracket into released position.

4. The combination with a supporting member having a slot, of a bracket, a pair of lugs on said bracket adapted to be inserted through said slot from one side of the supporting member and to engage the opposite side thereof when the bracket is turned, one side of each of said lugs having a cam portion to facilitate turning said bracket into locked position, and spring means carried by said bracket and rotatable therewith into a position to engage in said slots when said bracket is turned to carry said lugs into a position engaging said opposite side of the supporting member, said spring means having cam portions engageable with the side of the slots to facilitate turning said bracket into released position.

5. In combination, a supporting member having a generally circular opening therein and generally diametrically opposed notches, a bracket having a pair of attaching lugs, said lugs being adapted to pass through said notches when said bracket is mounted on said panel to engage said panel adjacent said notches when the bracket has been turned to carry the lugs away from the notches, and a spring member secured to said bracket and having two pairs of arms, one

pair being disposed relative to said lugs so that when said bracket is turned into locking position said pair of arms will drop into said notches to yieldingly hold said bracket in locked position, the other pair of arms engaging the side of the supporting member opposite said lugs and holding the latter against the supporting member while said first pair of arms are disposed in said notches.

6. The combination set forth in claim 5 further characterized by said supporting member consisting of a panel having a cup-shaped part secured to one side of said panel, said notches being formed in said cup-shaped part.

7. In combination, a wall-like supporting member having a hole therethrough, the bore of said hole having a plurality of grooves, a member to be supported comprising a portion adapted to be disposed in the bore of said hole and having lugs, said lugs being adapted to register with said grooves and to be passed through the hole in the support and to be rotated out of register with said grooves on the opposite side of the support, a resilient stop element mounted on said second member and being spaced from said lugs by not less than the length of the bore whereby said lugs and said element grip opposite sides of the first member, and a resilient locking lug carried by the second member adjacent the said element, said locking lug being out of register angularly with the first named lugs whereby the locking lug may drop into the adjacent end of a groove on the side of the supporting member opposite the holding lugs when the holding lugs are rotated out of register with the grooves.

8. In combination, a wall-like supporting member having a hole therethrough and a plurality of notches spaced around the circumference of

said hole, an element to be supported, said element being attached to a plate which is adapted to be supported by said supporting member in a plane substantially parallel to the plane of the supporting member and perpendicular to the axis of the hole, said plate having lugs offset from its circumference in a plane substantially parallel to that of the plate and being adapted to register with said notches, be passed therethrough and then rotated out of register with said notches on the opposite side of said support from said plate, a resilient plate positioned between said first plate and said lugs and being spaced from said lugs not less than the thickness of said supporting element, said resilient plate having on its circumference spring arms bent from the plane of said plates toward said lugs, all of said arms springing against one side of said support to hold the lugs up against the other side when the lugs are inserted through the notches of said support and rotated out of register therewith, some of said spring arms being additionally adapted to spring into said notches when said lugs have been rotated a predetermined amount, 20 cam means on one edge of each of said lugs to facilitate rotation of said lugs out of register with said notches, and cam means on said second named set of spring arms for both locking said first plate and supported element into fixed position against said supporting member and for camming said spring arms out of said notches when disengagement of said supported and supporting elements is desired.

35 WALTER NEWMAN,
*Administrator of the Estate of Harold Catron,
Deceased.*

FRANK A. DOTTERER.
